(57) **CLAIM**

The ornamental design for a rack base, as shown and described.

DESCRIPTION

FIG. 1 is a perspective view of the rack base showing my new design;

FIG. 2 is a front elevational view thereof;

FIG. 3 is a left elevational view thereof;

FIG. 4 is a right side elevational view thereof;

FIG. 5 is a top plan view thereof;

FIG. 6 is a bottom plan view thereof; and,

FIG. 7 is a perspective view of the design in state of use. The broken lines are for illustrating environment structure only and form no part of the claimed design.
